UNITED STATES PATENT OFFICE

2,668,358

APPARATUS FOR GAUGING

Frederick D. Moyer, Chicago, Ill., assignor to
 Chicago Bridge & Iron Company, a corporation
 of Illinois

Application September 16, 1949, Serial No. 116,006

1 Claim. (Cl. 33—126.5)

1

This invention relates to a gauging device and more specifically to a device for gauging a floating roof storage tank.

Floating roof storage tanks are widely used for the storage of volatile liquids, such as petroleum products, to reduce evaporation and filling losses of the stored liquid. Such tanks consist of a circular vessel having a roof which is unattached to the vessel but floats on the surface of the liquid therein contained and thus reduces or eliminates the vapor space above the surface of the liquid.

It is desirable practice in the operation of a floating roof tank to determine periodically not only the depth of liquid within the tank but also the amount of ice or other material which may have accumulated on the bottom of the tank through the freezing of drain water or through the introduction of sediment. Gauging the depth of liquid by dropping a gauge tape through a well in the roof, while indicating the distance between the upper and lower surfaces of the stored product, gives no indication of the depth of accumulations of ice or other matter on the bottom of the tank. Ice accumulation presents a major problem particularly where floating roof tanks are designed to permit rain water falling on the roof to flow to the bottom of the tank either through the stored liquid or through a drain connected to the roof and opening to the bottom of the tank. The depth of this accumulation is important to know inasmuch as the inlet and outlet of the tank are usually located a short distance above the bottom and thus knowledge of the depth of ice accumulation is a forewarning against possible operational difficulties.

I have invented and am herein describing and claiming an apparatus which not only gives accurate readings of the depth of the liquid but also indicates quite accurately the actual depth of bottom accumulations.

The invention will be described in conjunction with the accompanying drawings in which:

Figs. 1 and 2 are vertical sections through a portion of a floating roof tank and floating roof showing the operation of the apparatus of this invention in a tank with and without an ice accumulation in the bottom; and

Fig. 3 is an enlarged detailed view of the upper left hand portion of Fig. 1.

Referring now to the drawings I show a floating roof tank 10 having a flat bottom 11 and a cylindrical sidewall 12. A floating roof 13 is located within the tank and floats on the contained liquid 14. The roof is provided with an upper deck 15, a lower deck 16, and a gauge well 17 extending

through the decks. Attached to the upper portion of the sidewall 12 is a gauger's platform 17 accessible by means of a spiral ladder (not shown) leading therefrom to the ground.

5 Secured to the upper portion of the sidewall adjacent the gauger's platform is a triangular plate 18 which supports a bracket 19 extending horizontally inward towards the center of the tank. A lug 20 is welded or otherwise secured to the bracket and supports a hinge 21 having one end secured to the lug and having the other end secured to a bench mark 22. The bench mark is provided with a straight upper edge 23 in which is located a spirit level 24 for indicating the horizontal alignment of the bench mark.

Means are provided for adjusting the bench mark about the hinge 21 to bring it into perfect horizontal position, the means consisting of a threaded nut 25 welded to the inner end of the 20 bracket 19 through which a threaded shaft 26 extends, the shaft having its upper end 27 bearing against the bottom edge 28 of the bench mark. To hold the bench mark down tightly against the end of the shaft 26 I provide a compression spring 29 which has one end secured to a post 30 upstanding from the bracket and has its other end bearing against a plunger 31 which in turn bears against the upper surface 23 of the bench mark. The plunger is slidable 30 in a bushing 32 secured to the post 30.

It can thus be seen that the bench mark may be leveled by adjustment of the threaded shaft 26 to rock the bench mark about the pivot defined by the hinge 21 until the bubble in the spirit level is brought to the center.

35 A gauge tape 33 equipped with a plumb 34 may be dropped downwardly from the bench mark through the well 17 to the bottom of the tank. The gauge tape is appropriately marked so that 40 readings may be taken therefrom.

The bench mark 22 is located a predetermined distance above the bottom 11 of the tank and thus at all times the distance between the bench mark and the true bottom is known.

45 The method of gauging the tank using my device to determine the depth of accumulations, if any, on the bottom of the tank and the amount of liquid in the tank is as follows: Assuming that the distance from the bottom 11 to the bench mark is, for example, 50 ft., the gauge tape 33 is lowered through the well 17 until the plumb strikes the bottom of the tank. The distance from the bottom of the tank to the level of liquid in the well is then measured together with the 50 distance from the level of the liquid to the bench

mark. These two distances when added together should equal 50 ft.

However, should there be an accumulation of ice or other matter on the bottom of the tank, such as illustrated in Fig. 2, the distance from the plumb 34 to the level of the liquid plus the distance from the level of the liquid to the bench mark would not equal 50 ft. If the sum of these distances were, for example, 48 ft. it would then become known with certainty that two feet of ice had accumulated on the bottom of the tank.

While I have shown and described certain embodiments of my invention, it is to be understood that it is capable of many modifications. Changes, therefore, in the method, construction and arrangement may be made without departing from the spirit and scope of the invention as disclosed in the appended claim.

I claim:

In a floating roof tank having sidewalls, a roof and a gauge well in the roof, a gauging device comprising a bracket secured to the sidewall and having a portion extending substantially inwardly over the tank roof, a bench mark member hingedly attached to said bracket at the end thereof secured to said sidewall and extending

inwardly of said tank over said portion of said bracket, a bubble level secured to and extending longitudinally of the bench mark member, and means for accurately moving said bench mark member about said hinge connection relative to said portion to level the bench mark member.

FREDERICK D. MOYER.
